UNITED STATES PATENT OFFICE

156,771

WASHING MACHINE

Ray C. Sandin, Oak Park, Ill., assignor to Hot-point Inc., a corporation of New York

Application October 14, 1948, Serial No. 149,117

Term of patent 14 years

(Cl. D49—1)

To all whom it may concern:

Be it known that I, Ray C. Sandin, a citizen of the United States, residing at Oak Park, in the county of Cook, and State of Illinois, have invented a new, original, and ornamental Design for a Washing Machine, of which the following is a specification, reference being had to the accompanying drawing, forming a part thereof.

In the drawing, Figure 1 is a front perspective view of a Washing Machine, showing my new design; and

Fig. 2 is an enlarged vertical sectional view taken through the upper portion thereof along the line 2—2 in Fig. 1.

I claim:

The ornamental design for a washing machine, substantially as shown and described.

RAY C. SANDIN.
